CHARLES H. LOCHER, OF HANCOCK, MARYLAND, AND JOHN P. BURT, OF KEARNY, NEW JERSEY; SAID BURT ASSIGNOR TO HARNISCHFEGER CORPORATION, OF MILWAUKEE, WISCONSIN, A CORPORATION OF WISCONSIN

TROLLEY HOIST

Application filed September 15, 1926. Serial No. 135,517.

This invention relates to improvements in trolley hoists, and more particularly to the control therefor and the apparatus for supporting the bucket and dumping the load.

Trolley hoists of the type commonly used for operating grab buckets are mounted on an overhead track for movement along the same and comprise generally two units, each consisting of a motor with an electric brake, a controller, a cable drum and a train of reduction gears connecting the drum to the motor for operation thereby, suitable manually-operable control levers being provided whereby the drums may be operated independently of each other.

In using certain types of buckets, as for example skip buckets in a trolley hoist, a slight difference in the rate of operation of the motors in hoisting causes pulling in on one cable or line at a greater rate than on the other thus tilting the bucket and often-times dumping part of the load prematurely, thereby endangering the lives of workmen below. Another difficulty encountered in using a skip bucket in a grab bucket hoist is that there is an objectionable side sway to the skip so that when the latter is run within the narrow confines of the trolley supporting bridge or structure it has a tendency to sway sideways and strike one of the structural members, thus causing it to dump part of its load.

One of the objects of the present invention, therefore, is to provide, in a trolley hoist of the character referred to, improved means for controlling the motors whereby the same may be operated simultaneously at the same rate to adapt the hoist for skip bucket work.

Another object is to provide, in a hoist of the character referred to, improved means for suspending or supporting a skip bucket therefrom whereby side-swaying of the bucket is eliminated to a large extent.

Another object is to provide an improved hoist of the character referred to for operating a skip bucket, and which is readily controlled to prevent premature dumping or tilting movement of the bucket, and further to provide apparatus of the character described wherein the bucket may be moved through a

complete cycle, that is, from point where filled to dumping point and return in less time than has been possible heretofore without danger of tilting or objectionable side swaying.

Other objects and advantages will herein after appear.

For the purpose of illustrating the invention one embodiment thereof is shown in the drawings, in which

Figure 1 is a side elevational view, partly diagrammatic, some of the parts being removed for the sake of clearness;

Fig. 2 is an elevational view looking towards the left in Fig. 1, some of the parts being removed for the sake of clearness;

Fig. 3 is an end elevational view of the control mechanism for the motors; and

Fig. 4 is an elevational view partly in section and looking towards the left in Fig. 3, the section being taken on the line 4—4 in Fig. 3.

The trolley hoist is shown diagrammatically in Fig. 1 as comprising the two separate units which are mounted for movement together along an overhead track or bridge (not shown) of well known construction, one unit comprising the holding drum 10, the operating motor 11 therefor, and the train of gears 12, 13, 14 and 15 connecting the drum to the motor for operation thereby, the other unit comprising the tripping drum 16, the operating motor 17 and the train of gears 18, 19, 20 and 21 connecting the drum to the motor for operation thereby.

The pair of cables 22 and 23 are fixed at their upper ends to drum 10 for winding thereon as more clearly shown in Fig. 2, and are trained about sheaves 24 and 25 journaled respectively in frames 26 and 27 carried by and spaced along the bail 28 from which the skip bucket 29 is suspended by the chains 30, 31 and 32. The chains 30 and 31 are secured at their upper ends to the ends of bail 28 by means of brackets 33 and are secured at their lower ends to the rings 34 secured to the sides of the bucket forwardly of the center of gravity thereof. The chain 32 is connected at one end to the bail 28 at a point intermediate the ends of the latter and at its other end to the ring 35 secured

to the rear end of the bucket, chain 32 being provided with the ring 36 for the purpose hereinafter explained.

The other ends of cables 22 and 23 are secured as shown to the equalizer bar 37. The cable or line 38 is secured at one end to the tripping drum 16 for winding thereon, as shown in Fig. 2 and at its other end to bar 37 intermediate the ends thereof.

The means for tilting the bucket into dumping position, as shown in dotted lines in Fig. 1, comprises the trip chain 39 connected to ring 36, forming part of chain 32, and to the equalizer bar through the piece of cable 40.

By reason of the construction just described, it will be seen that starting with the hoist in the position as shown in Fig. 1, simultaneous operation of the motors 11 and 17 at the same rate will cause similar operation of the drums 10 and 16 and winding up of the cables 22, 23 and 38 thereon at the same rate to lift bucket 29, at which time there will be no rotation of the sheaves 24 and 25. When the bucket has been raised to the proper height, both of the motors 11 and 17 may be stopped and held against any movement by the usual electric brakes with which each is provided, and the trolley hoist moved along the overhead track or bridge to carry the bucket to the dump. The bucket is caused to tilt or move to dumping position by operating only the motor 17 to pull in on the cable or line 38 and raise the equalizer bar 37, thereby causing rotation of the sheaves 24 and 25 and taking up the slack in the flexible element or trip chain 39. When all the slack has been taken out of the trip chain 39, there is a direct connection from the rear end of the bucket to the tripping drum 16 through cable 38, equalizer bar 37, the cable 40, trip chain 39, and the part of chain 32 below ring 36 so that upon continued operation of the trip drum the rear end of the bracket is lifted to move the bucket to dumping position as shown in dotted lines in Fig. 1. After dumping its load, the bucket is returned to the position thereof shown in full lines by reversing motor 17 to cause reverse rotation of tripping drum 16, motor 17 being operated in this manner until the equalizer bar 37 is sufficiently close to sheaves 24 and 25 to place an appreciable amount of slackness in the trip chain 39, at which time motor 17 is stopped and the trolley hoist moved back along the overhead track to the place from whence it first came, both of the motors 11 and 17 then being reversed at the same instant and at the same rate to cause unwinding of the cables 22, 23 and 38 from the drums at the same rate to lower the hoist, at which time there is no rotation of sheaves 24 and 25.

From the foregoing it will be seen that the bucket 29 is raised and lowered by operating motors 11 and 17 simultaneously in the

proper direction and at the same rate, and that the bucket is moved to dumping position, as shown in dotted lines in Fig. 1, and returned to its normal position by operating only the motor 17 first in the hoisting direction and then in the opposite or reverse direction.

The mechanism or control for operating the motors in the manner just explained is shown in Figs. 3 and 4, and includes the shaft 41 journaled at its ends in the members 42 and 43 which may be part of the framework of the trolley hoist, and the manually-operable levers 44, 45 and 46 loosely mounted on this shaft, the levers 44 and 45 being connected with the usual controllers (not shown) for the motors 11 and 17 by the rods 44' and 45', respectively, whereby the motors are operable independently of each other, lever 44 being actuated to operate motor 11 and lever 45 being actuated to operate motor 17. The arrangement is such that the motor controllers are similarly set to operate the motors at the same rate in one direction or the other when levers 44 and 45 are in a certain angular relationship with respect to each other, this relationship in the present construction being when the levers are in the same plane. For the purpose of holding or locking levers 44 and 45 in this relation with respect to each other, quadrants 47 and 48 are keyed on shaft 41 and provided with the adjustable plates 49 and 50, respectively, provided with the notches 51 and 52 for receiving the latches 53 and 54 carried by the levers, the plates 49 and 50 being adjusted so that their notches 51 and 52 are aligned to receive latches 53 and 54 when levers 44 and 45 are positioned in the same plane, at which time latches 53 and 54 are permitted to enter these notches whereby the levers are locked for movement together. The latch 53 is urged at all times into latching position by the spring 55 compressed between the bracket 56 and lug 57 through which the actuating rod 58 for the latch loosely passes, rod 58 being pivotally connected at its upper end at 59 to a manually-operable lever 60 which is moved against the hand grip 61 at the upper end of lever 44 to raise latch 53 out of notch 51 against the action of spring 55. The actuating means for latch 54 is identical to that just described for latch 53, the spring 62 urging latch 53 into latching position at all times, and the lever 63 being moved against the hand grip 53 at the upper end of lever 45 to raise latch 54 out of notch 52. The plate 49 is provided with the arcuate slots 65 taken about shaft 41 as a center, and is held in position by the bolts 66 passing through these slots and quadrant 47. When it is desired to adjust plate 49, the bolts 66 are loosened and the plate shifted in the proper direction and the bolts tightened again. The plate 50 is adjusted in the same

manner. Any inequalities of the parts between levers 44 and 45 and the controller contacts may be compensated for by adjusting plates 49 and 50.

The levers are in their neutral position when vertical and operate the motors in the hoisting direction upon movement to the right, as viewed in Fig. 3, and reverse the motors to lower the bucket when moved to the left of their neutral position. Starting with the levers in their neutral position as shown in Figs. 3 and 4, therefore, with the latches 53 and 54 in notches 51 and 52 to lock the levers against relative pivotal movement with respect to each other about the axis of shaft 41, movement of the levers to the right of the neutral position causes simultaneous starting and operation of the motors 11 and 17 at the same rate to lift the bucket. During the lifting of the bucket, the lever 46 may be actuated to operate the usual motor (not shown) for causing movement of the hoist along the overhead track toward the dump, this motor being operated through a controller connected through the rod 65 to lever 46. When the bucket has been lifted to the desired height and the dump has been reached, the operator releases or raises latch 53 and moves lever 44 back to neutral position, thus stopping motor 11. Continued operation of the motor 17 then causes movement of the bucket to dumping position in the manner explained above, after which lever 45 is moved to its extreme position to the left to reverse motor 17, latch 54 remaining in notch 52 whereby the quadrants 48 and 47 are carried around together with lever 45. When motor 17 has reversed sufficiently to cause return movement of bucket 29 to the full line position shown, lever 44 is also moved to the left until latch 53 drops into notch 51 under the action of spring 55, at which time the motors 11 and 17 operate synchronously at the same rate and the bucket lowered, lever 46 having been subsequently reversed to return the trolley hoist to its starting point. When the bucket has been lowered to the proper point, both levers 44 and 45 are returned to their neutral positions and the motors 11 and 17 are thereby stopped. If, for any reason, there is a greater pull on one of the cables 22 and 23 than on the other, the bar 37 will tilt slightly in the plane of the paper, as viewed in Fig. 2, thus compensating for any unevenness and preventing side sway of the bucket which would otherwise occur if the ends of the cables 22 and 23 were dead-ended on the bucket or its associated parts.

It will therefore be seen that improved control mechanism has been provided for a trolley hoist of the character referred to whereby a skip bucket may be used with the same efficiency and effect as a grab bucket, and that the skip bucket is held against undue side swaying and premature dumping, and

may be moved at full speed through its cycle of operation to dumping position and return.

One embodiment of the invention has been shown and described, but of course various changes may be made, such as in the size, shape and arrangement of parts without departing from the spirit of the invention or the scope of the claims.

The invention claimed is:

1. The combination with hoisting apparatus of the character described including cable drums and driving motors therefor, of manually-operable control levers for said motors, a shaft for supporting said levers for movement independently of each other, said levers being operable upon movement into a given relation with respect to each other to cause equal effective hoisting and lowering movement of said drums, and means cooperative with said levers for locking the same to the shaft in such relation. 75

2. A control mechanism for the driving motors of the cable drums of hoisting apparatus comprising a shaft, manually-operable control levers for said motors loosely mounted on said shaft for pivotal movement about the axis thereof and operable when in a given angular relation with respect to each other to cause equal effective hoisting and lowering movements of said drums, and means fixed on said shaft for coaction with said levers to hold the latter in said relation with respect to each other for pivotal controlling movement about said axis. 90

3. A control mechanism for the driving motors of the cable drums of hoisting apparatus comprising a shaft, manually-operable control levers for said motors loosely mounted on said shaft for pivotal movement about the axis thereof and operable when in a given angular relation with respect to each other to cause equal effective hoisting and lowering movements of said drums, means operable to lock said levers in said relation and comprising latches carried by said levers, quadrants fixed on said shaft and provided with notches arranged to receive said latches when said levers are in said relation, and means for withdrawing said latches from said notches. 105

4. In hoisting apparatus of the character described, a bail, a skip bucket suspended therefrom, a pair of sheaves carried by said bail and spaced along the same, a pair of drums, a rigid bar, a pair of cables trained about said sheaves and secured at their respective ends to one of said drums and to the ends of said bar, a third cable secured at one end to the other of said drums and at its other end to said bar at a point intermediate the ends of the latter, means for operating said drums independently of each other, and means operable upon operation of said drums in such wise as to haul in on the third 110 120 125 130

cable at a greater rate than on said pair of cables to tilt said bucket to dumping position, said last-named means comprising a flexible element connected at one end to said bar and at its other end to the rear end of said bucket.

5. A hoisting apparatus of the character described, comprising a pair of drums, a pair of cables connected to one drum, another cable connected to the other drum, an equalizer interconnecting the cables, a skip bucket suspended on the pair of cables, a flexible connection between the skip bucket and the other cable operating when tensioned to tip the skip bucket and dump the contents thereof, and means for selectively operating said drums simultaneously or independently whereby when said drums are simultaneously operated, the bucket may be raised and lowered 10 without tipping and when one of said drums is operated while the other remains stationary, the flexible connection may be tensioned to discharge the contents of the bucket.

6. A hoisting apparatus of the character described, comprising a pair of drums, a pair of cables connected to one of said drums, an equalizer bar connected to said pair of cables, a cable connected to the other drum and to the equalizer bar intermediate the ends thereof, an arrangement of sheaves suspended on said pair of cables, a skip bucket carried by said sheaves, and means for operating said drums.

7. A hoisting apparatus of the character described, comprising a pair of drums, cables connected to the drums, means for interconnecting the cables, a skip bucket, means for suspending the skip bucket on a pair of the cables connected to one of the drums, individual motors for driving the drums, manually operable control levers for said motors supported for movement independently of each other and also operable upon movement in a certain relation with respect to each other 40 to cause equal effective hoisting and lowering movements of said drums, releasable means operable to interconnect and lock said levers in said certain relation, hand grips mounted on the levers, and controlling the operation 45 of said releasable means, and means controlled by said other cable and cooperating with the bucket for tipping the bucket to discharge the contents thereof when one of the drums is operated while the other remains 50 stationary.

In witness whereof, we hereto affix our signatures.

CHARLES H. LOCHER.
JOHN P. BURT.
